BUILDING STRUCTURE

Anders C. Olsen, Ambler, Pa.

Application July 7, 1936, Serial No. 90,423
Renewed October 24, 1938

27 Claims. (Cl. 72—16)

The present invention relates to building structures and particularly to wall and partition constructions.

In the erection of homes and office and commercial buildings of the smaller types, it has heretofore been generally customary to utilize structural units fabricated of wood, which is a material the properties of which are well-known to all, and which may be easily and conveniently shaped as desired. The tendency in present-day construction, however, is to substitute for the wood, which is highly inflammable and subject to decay and attack by insects, more durable materials. Various attempts have been made to devise building structures formed entirely of fire-resistant materials but practical difficulties of numerous kinds, together with increased costs of such materials, have retarded such developments. It has been suggested, for instance, that light-weight studding of steel may with advantage be employed in the erection of buildings of smaller sizes instead of the customary wooden studding. It has also been suggested that coverings of asbestos, gypsum or other non-inflammable and insect-resisting materials may be used, such coverings being built up of individual members such as panels, clapboards, shingles, or the like, the individual units of which are successively applied to the supporting members in the erection of the structure. The costs of such materials in many cases are not unduly high when the durability thereof is kept in mind but many practical problems of assembly are presented since, as is obvious, the various supporting and covering members may not readily be secured together, if at all, by the usual securing means, such as nails, customarily made use of in the erection of wooden buildings.

The general purpose of the present invention is to provide a low cost and readily assembled building structure the individual elements of which are formed of materials which may not be readily secured together quickly, conveniently, and at low cost by means now available to the public.

Primarily the invention relates to outside wall constructions and to partition constructions, but certain of its features may be availed of in the construction of roofs and elsewhere in erecting buildings. In the erection of walls and partitions in accordance with the invention, light-weight studs of metal are employed and preferably the inside and outside coverings comprise panels or clapboards formed of material such as gypsum, asbestos, or the like, although the invention is not necessarily limited to such material and contem-

plates the use, in combination with the metal studding, of wooden panels or clapboards or similar building elements fabricated of light-weight inflammable materials. Novel means is provided for securing to the steel studding the various covering elements, this means being of such character that the ordinary skilled worker may affix to the steel studding, with great ease and rapidity, the various elements which together comprise the two covering layers. Various forms of the securing means may be made use of and by way of example several forms are illustrated in the accompanying drawings and will be hereinafter described in detail.

In the drawings:

Figure 1 is a perspective view of portion of an outside wall construction, looking from an inside point, portions of the inside wall covering having been omitted in order that the outside wall covering may be more clearly perceived;

Figure 2 is a partial vertical section through the same;

Figure 3 is a perspective view showing upon a larger scale certain details of the outside covering structure and securing means;

Figure 4 is a perspective view showing a modified form of securing means;

Figure 5 is an end view of portion of one of the metal studs, showing one form of the means employed for attaching to the stud certain of the inside panels;

Figure 6 is a section on line 6—6 of Figure 5;

Figure 6a is an elevation of a small portion of one of the panels, showing a slot formed therein for cooperation with the securing means;

Figure 7 is a perspective view of a small portion of a modified form of stud;

Figure 8 is a vertical section through portion of a partition or wall showing a modified form of panel securing means;

Figure 9 is a section on line 8—9 of Figure 8;

Figures 10 and 11 are perspective views of two elements of the securing means illustrated in Figures 8 and 9;

Figure 12 shows in elevation portion of an interior wall of the built-up panel type, and primarily intended to support a plaster coating, a further form of panel securing means being illustrated;

Figure 13 is a section on line 13—13 of Figure 12;

Figure 14 is a section on line 14—14 of Figure 12;

Figure 15 is a perspective view of the retaining

means made use of in the construction shown in Figures 12, 13 and 14;

Figure 16 is a transverse section through a clapboard construction of novel type adapted for use as an element of the invention;

Figure 17 is a partial vertical transverse section through an outside wall construction showing a further type of securing means for the attachment of the covering boards or panels to the studding;

Figure 18 is an elevation of portion of a stud, as viewed from the edge, one of the securing clips being shown; and

Figure 19 is a view of such securing clip from the outside, this clip being also illustrated in dotted lines in one of the positions which it assumes while being applied to the studs.

The light-weight steel studs 10 are preferably rolled sections and may have in cross-section any one of a number of different shapes. A very satisfactory light-weight steel stud may be formed, however, of two channel members, as indicated in Figures 6 and 7, the webs of the channels being cut away so as to be lattice-like in appearance. Preferably two of these channels are placed web to web, as shown, to form a single stud. This gives the stud a cross-section resembling that of an I-beam, and hence having a maximum strength as a column for a given weight of metal. The studs may be spaced apart as found convenient or necessary, and are secured at their upper and lower ends by any suitable means, which means is not illustrated, as it comprises no part of the present invention. The two channel members comprising each stud may be secured to each other or not, as desired, and in certain instances, the channel members may be spaced apart slightly, as indicated for instance in Figure 14. By the term "stud" as used herein, is meant any suitable type of upright designed and constructed in such manner that one form or other of my improved panel securing means may cooperate therewith.

As clearly shown in Figure 1 a covering of flat relatively large panels 11 all disposed in a common vertical plane is secured to the studs upon one side of the vertical plane defined by the studs, and a second covering, comprising a plurality of clapboards 12, is secured to the studs upon the opposite sides thereof. This last mentioned covering is suitable for the outside wall covering of a building structure while the covering which comprises panels 11 is primarily intended for an inside wall covering and in most cases will itself be covered with a thin layer of plaster.

The various clapboards 12 may have various lengths as in the case of the ordinary wooden clapboards, and are arranged in overlapping relationship for weather resisting purposes. Each of these boards has formed therein, adjacent its lower edge, a longitudinally extending kerf or slot, such as indicated at 13 in Figures 3 and 4, this slot extending to the inside face of the board and being inclined to this face, the inclination being such that, when the board is disposed substantially vertically as shown in Figures 1, 2, 3 and 4, the slot extends upwardly and outwardly from the lower margin of the inner face of the board. The slot is made sufficiently deep to receive a securing member hereinafter to be described but is not extended to such an extent that the clapboard is materially weakened. The securing elements by means of which this outside clapboard covering is attached to the ver-

tical structure comprising the studs 10 comprises a plurality of elongated members or elements 14 each of these elements having a marginal portion 14' which fits snugly within the kerf or slot formed in the clapboard with which it is associated, the main portion of the element, however, projecting rearwardly of the clapboard in a generally horizontal plane and extending from a point closely adjacent one stud to a point closely adjacent the next stud.

At its ends, each element 14 is provided with slots, one of which is indicated at 14² in Figure 3, and these slots fit around and closely engage the opposite faces of adjacent flanges of studs 10, being thereby locked against movement normally to the plane of the studs. As clearly shown in Figures 2 and 3, a mid-portion of each securing element or member 14 engages and rests upon the upper edge of the clapboard immediately below the same.

In assembling a number of clapboards and securing elements in the formation of a wall, the lowermost board or boards is of course first positioned—being based upon any suitable firm support. A series of securing elements 14 are next applied, along the upper edge of this tier. The second clapboard or tier of clapboards is next positioned, the flanges 14' of the securing elements 14 being slid or inserted into the grooves 13 provided for their reception. Following this, a further series of securing elements 14 are positioned intermediate the studs 10 along the entire length of the wall and a further clapboard or series of clapboards applied, this process being repeated until the wall covering is completed from bottom to top. Once the bottom board 12 has been positioned, the assembly of the remaining boards may be very quickly effected. The completed wall covering is rigidly secured to the studding, each board overlapping the next lowermost board and preventing outward movement thereof, and the lower edge of each board being secured firmly by the securing elements to the studs.

Each securing element 14 also comprises a weathering strip, bridging the joint between the lower inner face of one board 12 and the upper outer face of the board 12 immediately above it, and thereby preventing the entrance of air or moisture. Where the wall is to be insulated interiorly, it is not necessary to so design the elements 14 that they function as weathering strips, and instead of continuous members 14 extending from stud to stud, the members may be relatively short, as for instance cut off along the dotted line 16 of Figure 3. It is desirable also in the event that short members of this type are made use of to provide each with a flange such as indicated in dotted lines at 17, this flange being preferably struck downwardly out of the body of the member 14 and at right angles thereto, the flange being intended to contact with the inner face of the board 12 immediately below and to comprise a limiting stop preventing any outward movement of that end of the securing member remote from the stud.

In such cases also intermediate locking members such as indicated at 18 may be employed, member 18 comprising a relatively short metallic securing element having a portion 18' adapted to enter a groove formed in a board 12, a horizontally disposed portion 18² adapted to rest upon the upper edge of the next lowermost board and a tongue or flange 18³ adapted to engage the inner face of this board. The upper

edge of the vertically extending portion of the member 18 is adapted to rest against the inner face of that board 12 which is engaged by the tongue 18'. A number of these auxiliary locking members 18 may be employed when the distance between studs 10 is relatively great, and the non-continuous locking means is made use of, in order to render the wall covering quite stiff and rigid. Where the studs 10 are spaced apart normal distances, however, the use of members 18 will ordinarily not be necessary.

Where the wall covering just described is of great height, it may be desirable to positively secure one or more horizontal rows of supporting members 14 to the studs in order that the entire weight of the covered structure may not be transmitted downwardly to the lowermost board. Thus in Figure 1 the uppermost row of securing members are shown to have their ends provided with upturned flanges 14' which flanges are positively attached to the studs 10 and hence may not move vertically. In actual practice, however, it is found that if the slots 14' in the members 14 are made of such width that the edges thereof contact closely with the flanges of studs 10, there is little necessity for attaching any of the securing members 14 positively to the studs, inasmuch as the frictional engagement of the securing members and the studs is substantial and a considerable portion of the weight of each board is transmitted directly to the studs instead of to the board beneath it.

The inner panels 11 of the wall structure shown in Figure 1 are attached to the studs by means of clips 20. These clips are preferably formed as shown clearly in Figures 5 and 6, so as to fit closely around the aligned flanges at one edge of the stud, but are slidable vertically along the stud. The clips are formed of sheet metal and each is provided with two inclined, outwardly and upwardly projecting, tongues 20' these tongues being disposed substantially at angles of 90° to each other. The ends of the panels 11 are provided with tongue receiving kerfs, also inclined, one of these kerfs being indicated at 11' in Figure 6a. In assembling the panels, the end of each is brought into position so that the corresponding tongues 20' of two vertically spaced clips are caused to enter the kerfs 11' of the panel. The end of the horizontally adjacent panel is then hung upon the second or remaining tongues 20' of these same clips, the adjacent edges of the panels meeting along a vertical plane intermediate the tongues.

In positioning the panels, the clips are moved vertically of the studs to the desired positions and, after a panel is finally placed in proper position, the clips are permanently secured against movement longitudinally of the studs by any suitable means. Preferably each clip is secured against downward movement by a small ear, such as indicated at 22, comprising a portion of the outer margin of one of the flanges of the stud upon which it is mounted. A small metallic ear such as 22 may be readily turned out of the plane of the stud flange by a suitable tool, the metal of the flange being ductile and relatively thin. The panels 11 meet end to end only at the studs 10 and, where panels are employed which are of greater lengths than the distances between adjacent studs, intermediate clips are unnecessary, the panels being secured only at their ends and not at intermediate points. In assembling the panels, the lowermost panels are of course affixed first, and thereafter the panels

are built up in successive horizontal rows until the wall covering is completed. The wall covering may be formed of panels such as plaster board panels, and may be conveniently covered with plaster.

In certain standard types of construction, the use of clips 20 may be avoided and the panel supporting tongues formed directly upon the studs, as indicated for instance in Figure 7, the supporting tongues being indicated at 23. These 10 tongues may be formed upon the studs at the point of manufacture of the studs or may be struck outwardly from the studs after the studs are positioned in a building, by means of a suitable tool, the metal of which the studs are 15 fabricated being sufficiently ductile and thin to permit this.

A further means for securing panels to metallic studding is indicated in Figures 8 to 11 inclusive. The studs 10 are of the lattice type and the individual panels of which each stud is composed are slightly spaced apart as shown in Figure 9. An anchor plate 30, clearly illustrated in Figure 10, is adapted to be inserted through one pair of apertures in the lattice-like webs of adjacent studs, this plate being so dimensioned that it may be moved laterally through these apertures, which apertures are aligned, when being inserted, occupying a position substantially as shown in dotted lines in Figure 8.

Thereafter the anchor plate 30 is moved to the position in which it is shown in full lines in Figure 8, slots 30' and 30' formed in the lower and upper margins of the anchor plate being provided for the reception of portions of the parallel webs of the channel members and the anchor plate being thereby permitted to move to its final position, the body of the plate resting upon one pair of upwardly and outwardly inclined web members 10'. When so positioned the anchor plate locks the panels in fixed spaced relationship and thereby strengthens the stud against forces which tend to deflect it as a column. Anchor plate 30 has an inclined flange 30' along one margin and this flange, when the anchor plate is finally positioned as shown in Figure 8, extends upwardly in a substantially vertical direction.

Panels are indicated at 31 and each of these panels has its vertical edges slotted, as at 31', the adjacent panel edges being spaced apart as shown in Figure 9. Panel edge securing clips are indicated at 32, each of these clips having a tongue 32' which enters the slot 31' of the adjacent panel and a portion 32' which is provided at its lower end with a notch, having an inclined edge 32'. It is the function of these clips to secure the panel edges to the anchoring plate 30 and in the assembly of the panels and securing means a portion 32' of each clip is inserted into the slot 31' of the adjacent panel and thereafter moved downwardly so that the upper edge 30' of the anchor plate 30 is caused to enter the notch formed in the clip.

As previously pointed out, the inner edge 32' of this notch is inclined to the vertical and hence if clip 32 is forced downwardly, this edge will act as a cam surface, drawing the clip rearwardly, and hence drawing the associated panel firmly against the outer face of the adjacent panel 70 forming portion of the stud 10.

After both clips 32 have been positioned, a resilient member of box-like cross-section, indicated at 35, may be inserted within the slot intermediate the panel edges, this strip being so designed as to 75

automatically interlock with the clips 32 when finally positioned, as shown in Figure 9. When thus positioned, it comprises means for preventing accidental displacement of the clips and also 5 means for completely filling the slot intermediate the panel edges. The outer face of member 35 may be decorated if desired. In order to secure a panel-like effect, including horizontal joints, as well as vertical joints, a similarly formed horizontally 10 extending member 35 may be inserted into a bridging member 36 extending horizontally between vertically spaced panels. Bridging member 36 has flanges 36' adapted to enter slots formed in the parallel horizontal edges of the vertically spaced panels and serves to maintain these panels in fixed spaced relationship, also providing a housing for the reception of the resilient decorative filling strip 35.

If it is not desired that the panels be separated 20 by the horizontally extending members 35, these members and the bridging members 36 may be omitted and the horizontal edges of the panels allowed to meet. The panel attaching means just above described may be employed for the attachment to the studding of plaster boards, or 25 may be employed for the attachment of decorative panels not intended to be covered by plaster coatings. When this last effect is desired, the filler strips 35 may be of decorative nature and 30 ornamented.

An inexpensive means for and method of securing panels in place is illustrated in Figures 12 to 14, inclusive, this means and method being particularly advantageous in erecting wall coverings 35 which are in turn intended to be coated with plaster.

Here the studs preferably comprise separated panels, as shown in Figures 12 and 14, which 40 panels are of the lattice-type or provided with apertures in the webs thereof. The panels are indicated at 40 and a panel securing element is indicated at 41. This element is in the nature of a clip of sheet metal the midportion of which is adapted to lie within apertures formed in the webs 45 of the channels comprising the stud, from which midportion project the reduced extensions 41' which in turn terminate in the heads 41''. The clips are so positioned that the reduced extensions 41' lie intermediate the horizontal edges of adjacent panels and the heads 41'' lie without and 50 contact with the outer surfaces of the panels. The clips are somewhat resilient and, when positioned as shown in Figure 14, have sufficient spring to continually urge the panels against the 55 outer vertical faces of the panels comprising the stud. The reduced extensions 41' hold the panels in spaced relationship so as to provide horizontal slots therebetween and the vertical edges of two adjacent panels are likewise spaced apart as 60 shown. Through these slots plaster will pass when the plaster coating is applied to the surface of the wall covering thus built up, and the plaster layer will be firmly bonded to the supporting structure. The locking heads 41'' will of course be 65 covered by the plaster layer, which is indicated at 42, an inwardly projecting plaster rib or tongue being indicated at 42'.

The locking means illustrated in Figures 17, 18 and 19 is primarily intended for use in securing 70 clapboards to metallic studding. Each clip comprises a metallic plate 50 which may have any desired shape and may conveniently be substantially rectangular as shown, portions of this plate being struck downwardly and inwardly to form retaining flanges 50' and 50'' each of these flanges

having a portion extending parallel to the body of the plate and defining therewith a groove adapted to receive an edge of the stud 10. The flanges are so spaced relatively to each other that the longitudinal axis of plate 50 is vertically disposed when the flanges 50' and 50'' are locked about opposite edges of the stud. To place the clip in this position, it is only necessary to move it into contact with the edge face of the stud when in some such position as indicated in dotted lines in Figure 19, the locking flanges 15' and 50'' being spaced laterally of and at opposite sides of the stud. Thereafter the locking plate is revolved until it occupies the position in which it is shown in full lines, which is its operative position.

Each clip 50 has projecting from its lower edge a laterally extending portion or flange 50' which terminates in an upwardly and outwardly inclined portion 50'' adapted to engage and snugly fit within a kerf or slot formed in a clapboard member 51. Portion 50' of the clip bottom flange rests upon the upper edge of the clapboard 51 next below it and the several clapboards which together comprise the wall covering surface are supported in substantially the same manner, with respect to 2 each other, and with respect to the stud 10, as in the case of the form of the invention first described. After engagement of the tongue 50'' within the kerf or slot formed for its reception, clip 50 is held firmly against rotation due to such 3 interengagement with board 51, and hence may not be detached from the stud 10. In the event that it is thought desirable to support one or more of the boards directly upon the studs instead of 4 permitting the weight thereof to rest upon the board or boards below, this may be readily brought about by nicking the edge of a flange of the stud and bending a portion of this flange edge laterally to form an ear such as indicated at 52, the upper edge of this ear contacting with the lower edge of the flange 50' and preventing downward movement of the clip upon the supporting stud. Any suitable tool may be provided for performing this function and the operation may be 5 quickly carried out in the field.

All of the embodiments of the invention may be made use of in the erection of buildings embodying metallic studding, but it will be obvious that certain forms are more useful for certain purposes than are other forms of securing means disclosed. The parts are of such type that they may be 60 readily and cheaply fabricated and large numbers may be boxed and shipped at small expense. The simplicity of the constructions suggested will appeal to the builder, and it is also clear that partition and wall structures can be erected rapidly, without the use of special tools or machinery, and without the use of welding apparatus, drills, bolts and the like. Furthermore, the panels and clapboards to be secured to the studs embody no 65 affixed parts, metallic or otherwise, which might be injured in shipment or erection. The kerfs or slots formed in the clapboards or panel members may be very easily and with slight expense placed therein during or immediately after manufactured.

While I preferably make use of such material as asbestos or gypsum in fabricating the clapboards and panels, the invention contemplates all suitable materials. Thus a suitable clapboard 70 may be formed by first forming a copper covering plate, such as indicated at 60 in Figure 16, providing the same with an interior and upwardly and outwardly inclined slot 60', and thereafter filling this covering plate with a material such as 75

gypsum, indicated in 61. The panels and clapboards of wood or any of the well-known fibrous materials may be readily secured in position by the means shown, although I prefer to make use of fire-proof materials.

After both the inside and outside covering layers of the wall have been assembled, the interior space may be secured with an insulating material such as mineral wool and the resulting structure is not only strong and rugged, but is weather-resisting, fire-proof and insulated against the passage of heat.

Having thus described the invention, what is claimed as new and desired to be secured by Letters Patent is:

1. In a wall structure, in combination, spaced vertically extending studs, tiers of horizontally extending clapboards in overlapping relationship, and means associated with each clapboard for attaching the same to the studs, said means including securing elements detachably connected to the clapboards and detachably connected to the studs.
2. In a wall structure, in combination, spaced vertically extending studs, tiers of horizontally extending clapboards in overlapping relationship, and means associated with each clapboard for attaching the same to the studs, said means including a securing element connecting each board to a stud and resting upon the upper edge of the board next below.
3. In a wall structure, in combination, spaced vertically extending studs, tiers of horizontally extending clapboards in overlapping relationship, and means associated with each clapboard for attaching the same to the studs, said means including a securing element which projects into a recess in a clapboard and interlocks with a stud, said means being readily detachable from both clapboard and stud.
4. In a wall structure, in combination, spaced vertically extending studs, tiers of horizontally extending clapboards in overlapping relationship, and means associated with each clapboard for attaching the same to the studs, said means including a horizontally extending metallic securing element interlocking with a stud and penetrating a clapboard from the inside.
5. A wall structure comprising studs, clapboards, and securing elements, a securing element resting upon the upper edge of each board and directly connecting the stud to the lower margin of the board next above.
6. A wall structure comprising flanged steel studs, clapboards arranged in overlapping relationship, and metallic securing elements detachably interlocked with the flanges of said studs and extending into apertures formed in the rear faces of said clapboards.
7. The combination with a flanged steel stud of a clip thereon and having a flange projecting outwardly to engage within a recess in a clapboard having a recess intermediate its edges, a clapboard penetrated by said flange, and a clapboard beneath and supporting said flange.
8. The combination set forth in claim 7 in which the clip is normally vertically slidable but is restrained against downward movement by a deformed portion of said stud.
9. A clip for attaching clapboards to flanged studs comprising a metallic plate having a flange extending at substantially a right angle thereto for engaging a clapboard and opposed flanges for projecting into a recess formed in the rear face of opposite edges of a stud.
10. In a wall structure, in combination, a stud comprising spaced parallel metallic members having aligned apertures, an anchor plate extending through said apertures and interlocking with said members, panels having adjacent edges paralleling said members respectively, and means securing said panel edges to said anchor plate.
11. In a wall structure, in combination, a stud comprising spaced parallel metallic members having aligned apertures, an anchor plate extending through said apertures and interlocking with said members, panels having adjacent edges paralleling said members respectively, and clips interlocking with said panel edges and said anchor plate whereby the panels are secured to said stud.
12. In a wall structure, in combination, a stud comprising spaced parallel metallic members having aligned apertures, an anchor plate extending through said apertures and interlocking with said members, panels having adjacent edges paralleling said members respectively, spaced clips interlocking with said panel edges and said anchor plate, and a member intermediate said clips and normally holding them in interlocking engagement with said panels.
13. In a wall construction, in combination, a vertical stud, vertically spaced panels, and a clip passing around the stud and having portions projecting outwardly between the panels, each such portion having a head at its end engaging the outer faces of both panels.
14. In a wall construction, in combination, a vertical stud, vertically spaced panels, a resilient metallic clip passing around the stud and having portions thereof projecting outwardly between the panels, and heads at the ends of said portions, each of which engages the outer surfaces of both panels, the clip resiliently urging both panels into close contact with the stud.
15. A stiffener for walls having clapboard coverings comprising a substantially L-shaped metallic member having a groove entering flange, a board edge engaging portion, and a board side engaging portion.
16. In a wall construction, a clapboard having a recess in its inner face and spaced from its lower edge, a lower clapboard the upper margin of which overlaps said first clapboard and has its upper edge closely adjacent the recess in said first board, and a metallic stiffener resting upon the upper edge of said lower board and having a portion extending within said recess and a second portion resting against the face of said first board above said recess.
17. A wall structure comprising studs, clapboards arranged in overlapping relationship, and means supporting each clapboard upon the one below it and connecting the same to the studs, each such means likewise sealing the joint between two superposed clapboards.
18. A wall structure comprising in combination, spaced studs, tiers of horizontally extending clapboards in overlapping relationship, and means associated with each clapboard for attaching the same to the studs, said means comprising elongated members spanning the spaced studs and having formed portions thereof detachably connecting to the clapboards and to the studs, respectively.
19. A clapboard wall facing comprising overlapping clapboards, the rear faces of said clapboards being provided with inwardly and upwardly extending inclined slots, clip members having outwardly and upwardly extending in-

clined flanges adapted to enter the slots in said clapboards, and means for detachably supporting said clip members and through them said clapboards.

5 20. A clapboard wall structure comprising spaced stud members, overlapping clapboards and means securing said clapboards to said studs, the upper portion of a clapboard being held against said studs by the overlapping lower portion of an adjacent clapboard, the securing means and each clapboard having mutually engaging inclined wedging surfaces whereby the wedging action thereof draws the lower portion of said clapboard inwardly toward the studs to clamp the 10 upper portion of the next lower clapboard between the rear face of said first clapboard and said studs.

15 21. In a clapboard wall construction, clapboards, the lower margins of an upper clapboard overlapping the upper margin of a lower clapboard, the overlapping clapboard having in its rear face an inwardly and upwardly extending inclined slot, and means for securing together the overlapping faces of said clapboard, the said 20 means comprising a clip having an outwardly directed upwardly inclined flange thereon and spaced therefrom a second but downwardly directed flange, the overlapping clapboards being secured in contact through the engagement of the 25 said inclined flange in the said inclined slot of the upper clapboard and the engagement of the downwardly directed flange with the upper margin of the lower clapboard.

22. In a wall construction, a stud, wall-forming 30 material mounted thereon, and means outstanding from said stud and provided with outwardly and upwardly inclined flanges, said wall-forming material having inwardly and upwardly extending slots formed therein, said wall-forming material being secured against the said stud by mutual engagement of said slots and said flanges.

35 23. A wall stud having a face portion against which sheet form wall-forming material is adapted to be mounted, the said stud being provided 40 with outwardly and upwardly directed tongues extending outwardly beyond the plane of the said face portion adapted to receive the sheet form wall-forming material, the inner face of the upwardly directed, outwardly extending tongue constituting an inclined cam face whereby upon 45 50 mounting thereon a sheet of wall-forming mate-

rial having a complementing slot, the action of the said cam face will be to continuously urge the sheet into engagement with the face portion of the stud.

24. In a wall construction, in combination, a stud having a web and oppositely disposed outwardly extending flanges formed thereon, said flanges being in substantially the same plane, and clips mounted against the outer face of said flanges and having portions extending around said flanges and behind the rear faces thereof, said clips having outwardly and upwardly extending mounting means thereon.

25. A wall construction unit comprising a pair of channel form members spaced one from the other, the webs of said channel members having apertures therein, and slotted tie plates extending through opposed apertures, said tie plates having slots therein engaging the webs of said channel members, said channel members and tie plates forming a unitary structural member.

26. In a wall structure, studs, wall-forming sheet material mounted thereon, and clips securing said sheet material to said studs, each said clip comprising a body portion and a flange portion, said flange portion being angularly displaced with respect to the body portion and being adapted to engage said wall-forming material, said body portion having a tapered slot extending upwardly therein, clip mountings supported on 3 said studs rearwardly of the face thereof and adapted to engage said slots in said clips, whereby when said clips are moved downwardly on said clip mountings there is effected an approach of the flanges of said clips toward the face of said 3 studs.

27. In a wall construction, spaced studs and sheet form wall-forming material mounted thereon, the sheet form wall-forming material spanning a pair of adjacent studs and having in its rear face an inwardly and upwardly inclined slot therein, co-acting mounting means therefor, spanning between adjacent studs, its respective ends formed for mounting on the studs, said mounting means having an upwardly and outwardly inclined lip portion complementing the slot, the engagement of the slot and lip constituting a mounting wedgingly engaging a sheet against the face of the studs.

ANDERS C. OLSEN. 50
